B. MARTIN

GLASS DOORKNOB

Filed Jan. 13, 1923

FIG. 1

FIG. 3

FIG. 4

INVENTOR
B. MARTIN

BY Wright Brewer

ATTYS

UNITED STATES PATENT OFFICE.

BERENT MARTIN, OF SAN FRANCISCO, CALIFORNIA.

GLASS DOORKNOB.

Application filed January 13, 1923. Serial No. 612,428.

To all whom it may concern:

Be it known that I, BERENT MARTIN, a citizen of the United States, residing at San Francisco, in the county of San Francisco and State of California, have invented new and useful Improvements in Glass Doorknobs, of which the following is a specification.

This invention relates to improvements 10 in glass door knobs and resides in the provision of improved means for fastening glass door knobs to the knob spindles which means is simple as to construction, inexpensive and such that substitution of a glass, 15 or breakable knob, for a knob of other or unbreakable material may be easily made without necessitating changing the spindles.

One of the objects of the invention is to provide glass door knob fastening means of 20 the character described which will not only provide for a secure and effective detachable fastening of the knob to the ordinary type of knob spindle but protect the knob against breaking or cracking in the event 25 the knob is moved forcibly against the wall and in the event of an excessive sidewise or other strain or pressure being transmitted to the knob.

The present style of glass door knob 30 fastening is one in which the fitting is permanently fastened to the knob and is provided with a screw threaded opening to receive a screw threaded portion of the spindle, the fitting being held in place by a 35 set screw. This fastening arrangement permits the knob to work loose on the spindle after constant use of the knob or upon continual subjecting of the same to strains and pressures. To equip a door having the metal 40 or other types of knobs, with glass knobs, it is necessary to replace the old spindle with a spindle having threaded ends specially adapted for glass knobs. My invention takes into consideration the provision for 45 fastening glass knobs to the ordinary type of knob spindle without requiring the substitution of the special type of spindle and in this eliminates the necessity of employing specially constructed parts and permits 50 of a less expensive fitting of doors with glass knobs and at the same time provides for a protection of the knob against accidental breakage or loosening.

The invention possesses other advantages 55 and features some of which, with the foregoing will be set forth at length in the fol-

lowing description where I shall outline in full that form of the invention which I have selected for illustration in the drawings accompanying and forming a part of 60 the present specification. In said drawings I have shown one form of the construction of my invention, but it is to be understood that I do not limit myself to such form since the invention as expressed in the claims may 65 be embodied in a plurality of forms.

Referring to the drawing:

Fig. 1 represents a top plan view of the 70 knob of my invention as applied to a door, part of which latter is shown.

Fig. 2 represents a cross sectional view of the knob of my invention.

Fig. 3 represents an end elevation of the fitting member.

Fig. 4 represents a perspective view of an 75 ordinary type of knob spindle having extra holes provided therein.

Referring to the form of the invention shown in the accompanying drawing, 1 designates a door knob formed of glass or other 80 breakable material, which knob is given a fanciful shape and appearance and has a protuberance 2 on its outer face. In the opposite or inner face of the knob there is provided a socket 3 which socket, adjacent 85 its outer end, is enlarged as at 4 and provided with a series of radial teeth 5 in said enlarged portion. Through the central portion of the knob is a bore or opening 6 adapted to receive a screw 7 which is utilized 90 to fasten the knob in place, said screw having a thin head 8 which is curved and conforms somewhat to the curvature of the protuberance 2, but which projects beyond 95 the protuberance so that it will strike against the wall or other object against which the door is slammed, and protect the knob from being broken or cracked.

A special fitting is provided for attaching the knob to a spindle 9. This fitting 100 comprises a circular body portion 10 having a reduced extension 11 at its inner end defining a shoulder 12 and also having an annular flange 13 at its outer end. The outer face of the flange is provided with radial teeth 15 which engage and interlock with the teeth 5 in the enlarged portion of the socket in the knob. The flange 13 extends slightly into and fits snugly in the enlarged portion 4 of the socket. Projecting 105 outwardly from the central portion of the outer end of the member 10 is a cylindrical 110

protuberance or projection 16 which extends well into but is spaced circumferentially from the walls of the socket 3. This projection is provided with a central longitudinally disposed screw threaded opening 17 which receives the screw threaded end 18 of the screw 7. Extending longitudinally through the body portion 10 and opening out through the member 11 is a socket 19 which is of rectangular outline in cross section, and adapted to receive the spindle 9. This socket extends well into the protuberance or projection 16 and the opening 17 communicates with said socket. Upon tightening the screw 7, the fitting is drawn against the knob until a secure fastening of the knob to the fitting is provided and the parts will appear in relations as shown in detail in Fig. 2. By having the socket 19 comparatively long, it being as long as the fitting itself less the length of the opening 17, the spindle may be adjusted so that any one of its customary three set screw holes 20 may be brought into registration with an opening 21 provided in said body portion 10. A set screw 22 is mounted in the opening 21 and is adapted to be turned in any one of the openings 20, dependent upon the adjustment required of the spindle 9. To increase the range of adjustment of the spindle in order to secure a neat and tight fitting of the knob and its attaching means, I may provide in the spindle, extra set screw holes 23 which will extend 35 at right angles to and between the holes 20. With my type of knob it is only necessary to remove the old knobs and substitute the glass ones of my invention by inserting the ends of the whole spindle into the fitting attached to the knobs and adjusting the fittings so that the set screws may be tightened and the knobs held in place. Should the knob of my invention become cracked or broken, it may be readily removed and a new knob easily substituted, whereas with the type of glass knobs which are permanently fastened to the fitting, this type being now generally used, a new fitting has to be employed when the knob breaks. From

the foregoing it will be seen that the knob 50 of my invention provides advantages in construction and mode of application over the present styles of glass knobs.

By having the protuberance or projection 16 comparatively long, means is provided for effectively fixing the screw 7 in such manner that strains and stresses will be centrally and evenly distributed when the outer end of the screw strikes a wall or other object against which the door is slammed. 55 Aside from providing an effective means for attaching the screw, this projection 16 enables the provision of a long socket for reception of the spindle and thus facilitates the adjustment of the spindle in order that a neat and proper fitting of the knob on the door may be effected. By having the projection 16 spaced from the walls of the socket, all tendency of subjecting the knob to severe strains or to cracking of the knob, 60 incident to lateral or side pressures on the knob is eliminated.

I claim:

The combination with a glass door knob 75 having a socket extending inwardly from the inner side of the knob and provided with a reduced bore continuing through the knob from the inner end of the socket, said socket being enlarged at its outer end to form an annular recess having teeth on its surfaces, 80 and a door knob spindle, of means for attaching the knob to the spindle comprising a member having a spindle socket therein, means for securing the spindle in the socket, an annular flange on said member 85 extending into said annular recess and provided with teeth cooperating with teeth in said recess, a projection on said member extending forwardly from the flange into said socket and being spaced from the walls of 90 the socket, said projection having a screw threaded opening therein in alignment with the reduced bore in the knob and a screw in said bore having its threaded end turned in said screw threaded opening and its head 95 engaged with the outer face of the knob.

BERENT MARTIN.
